(57) **CLAIM**

The ornamental design for a fluorescent lampholder, as shown and described.

DESCRIPTION

FIG. 1 is a top view of a fluorescent lampholder in a selected tilted position showing the new design;

FIG. 2 is a bottom view of the fluorescent lampholder shown in FIG. 1;

FIG. 3 is a front view of the fluorescent lampholder shown in FIG. 1;

FIG. 4 is a side view of the fluorescent lampholder shown in FIG. 1, the opposite side being a mirror image of this side view; and,

FIG. 5 is a rear view of the fluorescent lampholder shown in FIG. 1.

Features shown in dash lines depict the environment and do not form part of the claimed design.
